United States Patent Office.

L. M. BATTY, OF CANTON, OHIO.

Letters Patent No. 66,283, dated July 2, 1867; antedated June 12, 1867.

IMPROVED RAILROAD SWITCH.

The Schedule referred to in these Letters Patent and making part of the same.

TO ALL WHOM IT MAY CONCERN:

Be it known that I, L. M. BATTY, of Canton, in the county of Stark, and State of Ohio, have invented a new and useful improvement in Railroad Safety-Switches; and I do hereby declare that the following is a full, clear, and exact description of the construction and operation of the same, reference being had to the accompanying drawings, and to the letters of reference marked thereon, making a part of this specification, in which—

Figure 1 is a plan view of the working parts.

Figures 2 and 3 are side elevations of the same; and

Figure 4 is a detached sectional view of a cover hereafter described.

My improvement relates to an arrangement of devices applied to the switch-lever and connecting-rod in common use, by which I make a cheap and effective switch, in which I obtain all the advantages that have been claimed by inventors of safety switches, with less expense than is required to construct the ordinary switches in common use.

In figs. 1, 2, and 3, A represents a railroad tie, to which a cast-iron post, B, is bolted or otherwise fastened, which takes the place of the ordinary framework used in the construction of switches, and to which the switch-lever C is hung in the usual manner, connecting as usual with the connecting-rod D. A treadle, E, is also attached to the post B by a flexible joint. The connecting-rod D being attached to the switch-rails 1 and 2 in the usual way, has secured on it an adjustable plate, F, having a notch, a, in the centre of its upper edge, which receives the inner end of the treadle, and thereby fastens the switch-rails to their proper place when the switch is closed, as seen in figs. 1 and 2. The notched plate F is also supplied with lugs b b, against which the inner end of the treadle operates as a stop when the switch is opened in either direction, as seen in fig. 3. The lugs b may be placed at any distance from the notch a, so that the switch-rails 1 and 2 may be placed at two, three, or more different tracks in the usual way. A spring, G, secured under the post B, operates on the treadle E to keep its inner end in the notch a. The upright shaft H operates as a lock to secure the switch from being opened by any one but the operator. The upper end of this shaft, being fitted to a turn-key, passes up through a box or hole, e, in the top of the cover M, shown in fig. 4. It also has a lug, d, on its lower end, which, to lock the switch, is turned around under and at right angles with the treadle E, as seen in fig. 2, and to unlock the switch the lug is turned around, as seen in fig. 3. The foot-piece of the treadle E is supplied with a loop, I, placed over the part filled by the instep of the operator's foot, which loop may be secured directly to the foot-piece, but is here attached to a spring, J, which is adjustably secured to the inner end of the foot-piece, as shown in figs. 2 and 3. A grapple, or more properly a hinged stop, K, being hinged at e, and being a continuous piece of iron, has its inner end passed through a slot-hole, f, in the treadle E, and having its outer part pass upward out and around the outer end of the treadle, as shown in the drawings. The cover shown in fig. 4 is secured over the outer end of the treadle E, with all its appendages, including the lock H, and thereby protecting them from accidents, and from the accumulation of snow and ice. The cover is also supplied with a lid, L, as shown in fig. 4.

To open the switch the operator unlocks it as above described, and raising the lid L with his foot or otherwise, and placing his foot under the loop I, and upon the foot-piece of the treadle E, presses it down and thereby relieves the inner end of the treadle from the notch a, and causes the outer end of the hinged stop K to rise up around the sides and back of the operator's heel or ankle. The switch is then opened in the usual manner, as shown in fig. 3. Meanwhile the operator's foot being held by means of the loop I and the hinged stop K, he is obliged to remain at his post with one foot in a trap and the other *on-terra firma* until the train is passed, when he can close the switch, lock it, and leave at his leisure.

The object of placing the loop I on a spring, as above described, is to allow the operator to extricate his foot in case of impending danger by a sudden jerk of the foot of sufficient force to overcome the elasticity of the spring. The advantages of this switch are already mentioned in the premises.

I do not claim priority in constructing a safety switch of any kind, for I am aware that it has been done by Milton Ball and others.

What I claim as my improvement, and desire to secure by Letters Patent, is

1. I claim the combination of the lever C, the post B, the connecting-rod D, and the treadle E, in the manner and for the purpose herein described.
2. I claim the adjustable plate F, with its lugs *b* and notch *a*, when combined with the treadle E and connecting-rod D, in the manner and for the purpose herein described.
3. I claim the treadle E, when combined with the several devices H, I, J, K, *e*, and *f*, in the manner and for the purposes herein set forth.
4. I claim the casing M, surrounding the outer part of the treadle D, to protect the treadle and devices H, I, J, K, *e*, and *f* from injury, as and for the purposes herein set forth.

L. M. BATTY.
